REFRIGERATING SYSTEM

Ralph F. Peo, Buffalo, N. Y., assignor to Houde Engineering Corporation, Buffalo, N. Y., a corporation of New York

Application November 13, 1935, Serial No. 49,503

6 Claims. (Cl. 62—115)

This invention relates to a device for introducing a refrigerant into refrigerating systems without permitting the introduction of air or other impurities together with the refrigerant.

5 More specifically, this invention relates to a check valve adapted to be disposed in the expanded refrigerant line from the evaporator unit of a mechanical refrigerating system.

Heretofore, in charging mechanical refrigerating systems with any refrigerant which operates below atmospheric pressure and which is liquid at atmospheric pressures and room temperatures, such as, for example, methylene chloride (CH_2Cl_2), a receiver or collecting tank has been provided in the refrigerating system with a plug opening at the top thereof. The refrigerant has been poured through this opening, after removing the plug, into the receiver until the desired charge was introduced. This procedure, however, always results in the introduction of air and other impurities into the refrigerator system, and materially decreases the efficiency of the system.

It was therefore necessary to purge the system free from air after the refrigerant had been introduced therein by warming the condenser of the system and running the compressor pump until the high side of the system was above atmospheric pressure. The plug at the top of the receiver was then removed, and since the pressure inside of the receiver was greater than atmospheric pressure, any air trapped at the top of the receiver above the liquid refrigerant therein would be blown out of the system. In order to complete the removal of air and other trapped gases in the refrigerant, it was necessary to repeat the purging operation in two or three successive steps.

This procedure involves considerable time and expense in running the compressor pump without obtaining any appreciable refrigerating effect, and I have therefore now provided a device for mounting in the refrigerating system which permits the charging of the system with refrigerant, while at the same time sealing the system against introduction of air or other impurities. According to my invention, liquid methylene chloride or similar refrigerant is sucked into the system through a check valve preferably secured to the intake opening of the compressor, and the system is, at the same time, sealed against introduction of air with the new charge of refrigerant.

It is therefore an object of this invention to provide a simple charging device permitting the

introduction of refrigerant into refrigerating systems while at the same time sealing the system against the introduction of air.

Another object of this invention is to provide a check valve device for attachment to the intake orifice of the compressor pump in a refrigerating system for introducing refrigerant into the system.

A further object of this invention is to provide a refrigerant charging device for mounting in the intake line to the compressor pump of refrigerating systems.

Other and further objects of this invention will be apparent from the following detailed description of the annexed sheet of drawings, which discloses a preferred embodiment of the invention.

On the drawing:

Figure 1 is a diagrammatic view of a refrigerating system having an intake check valve incorporated therein according to this invention.

Figure 2 is an enlarged cross-sectional view, with parts in elevation, taken substantially on the line II—II of Figure 1.

Figure 3 is a vertical cross-sectional view taken substantially along the line III—III of Figure 2.

Figure 4 is an enlarged fragmentary vertical cross-sectional view taken substantially along the line IV—IV of Figure 1.

As shown on the drawing:

In Figure 1, the reference numeral 10 indicates a rotary compressor pump having a discharge outlet 11 for flowing compressed refrigerant through a tube 12 into a condenser 13, wherein the refrigerant is cooled by air flowing around the condenser, and becomes liquefied. The liquefied refrigerant flows from the top of the condenser 13 into a tube 14 communicating with the receiver 15, where it is collected for use. As shown, the receiver 15 has a plug 16 near the top thereof which can be removed to purge the system of any air trapped in the refrigerant.

Liquid refrigerant collected in the receiver 15 flows through a tube 17 into an expansion valve 18, where it is expanded into the low side of the system through a tube 19 and into the bottom header 20 of an evaporator unit indicated generally at 21. The refrigerant in the header 20 expands upwardly through a plurality of heat exchanger tubes 22 and cools these tubes for performing its refrigerating function. The spent expanded refrigerant is collected at the top of the evaporator unit 21 in a header 23, and is sucked from the header 23 through a tube 24 into the check valve device of this invention, indi-

cated generally at 25. The device 25 is secured on the intake 26 to the compressor pump 10.

It should be understood from the above description that the compressor 10 reduces the pressure in the low side of the system between the expansion valve 18 and the intake 26 of the pump. The expanded refrigerant received by the pump is then compressed and pumped through the cooling coil 13, wherein it is again liquefied and collected in the receiver 15.

The system described is therefore of the expanded refrigerant type wherein compressed or liquefied refrigerant is expanded through an evaporator unit to absorb heat from the unit and perform its refrigerating function. The spent expanded refrigerant is then sucked into the intake side of a rotary compressor and discharged from the compressor at a pressure sufficient to cause its condensation in a condenser unit.

The intake check valve 25 of this invention, as best shown in Figures 2, 3 and 4, comprises a cast or forged metal housing 30 defining a chamber 31 therein with a recessed shoulder 32 at the bottom of the chamber 31 and a well or sump 33 at the base of the housing below said shoulder.

The recessed shoulder 32 receives therein an annular collar or valve seat 34 which may be pressed into tight frictional engagement with the recess of the shoulder. The valve seat 34 receives a metal plate or disk 35 adapted to lie upon an upturned lip 36 of the valve seat 34 and effect a sealing of the sump 33 from the chamber 31.

The top of the housing 30 is closed with a plate 37 which may conveniently be spun into or brazed onto the housing for sealing the chamber 31. A rod 38 extends through the central portion of the plate 37 and is brazed or soldered therein. The rod 38 carries a spider 39 at the bottom thereof spaced from the plate 35 a sufficient distance to allow this plate to rise and fall in the chamber 31, without permitting the plate to stand on edge. The spider 39 therefore acts as a top stop for the plate or disk 35.

An opening 40 of a comparatively large size is formed through the side wall of the housing 30 near the top thereof and communicates with a passageway 41 which may be conveniently formed integral with the housing 30. The passageway 41 terminates in an enlarged flange 42 adapted to be directly secured to the intake 26 of the pump 10.

As shown in Figure 2, the flange 42 has oppositely extending ears provided with openings 43 therein for receiving bolts (not shown) to secure the device 25 to the intake 26 of the pump 10.

As shown in Figures 1 and 4, the well or sump 33 has an opening 44 through the side wall thereof of near the bottom of the sump. This opening has a boss 44^a theretround, as shown in Figure 1, for receiving the tube 24 from the evaporator unit. The tube 24 may be sealed in the opening 44 by forcing the tube in the opening with the nut 45 secured on the boss 44^a of the housing.

The bottom of the sump 33 has a small threaded opening 46 adapted to receive in threaded relation therein the vertical branch 47^a of a coupling member 47. The branch 47^a has a vertical passageway 48 therethrough communicating with the sump 33 and with a horizontal passageway 49 of the branch 47^b of the coupling member.

This branch 47^b has an enlarged horizontal threaded bore 50 communicating with the passageway 49. A tapered seat 51 is formed at the

end of the bore 50 for receiving the tapered end 53 of a needle valve 54 which is threaded in the bore 50. The needle valve has a laterally extending shank 55 projecting beyond the end of the branch 47^b provided with an end 56 for receiving a wrench or tool to screw the needle valve 54 into the bore so that the end 53 thereof is in tight-fitting engagement with the seat 51 or to space the needle valve end 53 away from the seat 51.

A cap member 57 is threaded around the end of the branch 47^b and compresses a gasket 58 over the end of the branch 47^b to seal the bore 50 from the outside. The cap 57 has an extending portion defining a well 59 in which the end 56 of the needle valve may be disposed and protected against injury.

The coupling member 47 also has another vertical branch 47^c projecting from the bottom thereof and defining a vertical passageway 60 offset from the vertical passageway 48 but communicating with the bore 50. The branch 47^c receives a cap 61 in threaded relation theretround for pressing a coupling 62 against the end of the passageway 60 in air-tight relation therewith. The coupling 62 carries a tube 63 having its interior communicating with the passageway 60 through an opening provided in the coupling 62.

When it is desired to charge a refrigerating system such as shown in Figure 1 with refrigerant, the needle valve 54 is opened so that the passageway 60 of the coupling 47 communicates with the passageway 48 through the bore 50 and passageway 49. Before the needle valve is opened, however, the tube 63 communicating with the passageway 60 of the coupling 47 is disposed in a container 64 (Figure 1) for liquid refrigerant, such as methylene chloride, below the liquid level therein. The compressor pump 10 thereupon sucks refrigerant from the container 64 into the sump 33 of the device 25 and the check valve 35 thereupon opens to permit the refrigerant to flow through the passageway 41 into the inlet 26 of the pump. Since the tube 63 is maintained below the level of liquid refrigerant in the container 64, and since the refrigerant is sucked from the container, no air is introduced into the system with the refrigerant. After a sufficient amount of refrigerant has been introduced into the system, the needle valve 54 is closed and the check valve 35 thereupon drops by gravity to be seated on its seat 36. When the refrigerating system is operating, this check valve is only opened when the pressure in the evaporator is greater than the pressure at the intake of the pump. Under these conditions the spent expanded refrigerant from the evaporator opens the valve 35 and flows into the pump to be compressed. In the event that back pressure is built up in the pump it does not affect the operation of the low side of the refrigerating system since the check valve 35 will close and seal the evaporator from the pump until the pressure within the evaporator is greater than the pressure at the intake of the pump.

The device 25 therefor not only provides a means for charging the refrigerating system with refrigerant but also seals the low side of the system against back pressures built up in the pump. This sealing feature is important in the usual intermittent operation of the pump since after the pump is stopped any refrigerant collected in the intake thereof or leaking back from the high side expands due to the heat of the

motor and tends to increase the pressure in the low side of the system. The valve, however, seals the low side of the system from the pump until the pressure within the evaporator is greater than the pressure in the pump. As a result the reduced pressure in the low side is utilized completely to expand refrigerant in the evaporator for performing its cooling function.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In a mechanical refrigerating system of the expanded refrigerant type including an evaporator and a suction pump for removing spent refrigerant from the evaporator, a check valve interposed between the evaporator and the suction pump to arrest a back flow of material out of the pump and a tube communicating with the evaporator side of said check valve adapted to be connected to a source of refrigerant for charging the system.

2. In a refrigerating system of the expanded refrigerant type including an evaporator unit and a compressor pump in operative assembly, the improvement which comprises a check valve interposed between the evaporator and compressor pump to arrest a back flow of material out of the pump and a valved tube communicating with the evaporator side of said check valve adapted to be connected to a source of refrigerant for charging the system.

3. In a mechanical refrigerating system including an evaporator and compressor pump in operative assembly, the improvement which comprises a check valve interposed between the evaporator and the compressor pump to arrest a back flow of material out of the pump and a manually operable valve communicating with the inlet side of said check valve, said manually operable valve

adapted to open said inlet side of the check valve to a source of refrigerant.

4. In a mechanical refrigerating system including a compressor pump, the improvement which comprises a check valve having the outlet side thereof communicating with the inlet of said compressor pump, said check valve adapted to arrest a back flow of material out of the pump, and means communicating with the inlet side of said check valve for connection with a source of refrigerant to charge the refrigerating system.

5. In a mechanical refrigerating system including an evaporator unit and a compressor pump, the improvement which comprises a charging device interposed between the evaporator and the inlet side of said pump, said charging device comprising a housing defining an upper chamber and a well below said chamber, a check valve between said chamber and said well adapted to open upwardly only for connecting the well with the chamber, said housing having an outlet opening joining said upper chamber with the inlet to the pump, and an inlet opening joining said well with the evaporator, said housing also having a third opening communicating with the well and a valve coupling secured in said third opening adapted to be joined with a source of refrigerant.

6. The method of charging a mechanical refrigerating system of the compressor-condenser-evaporator type including a check valve having an outlet communicating with the intake side of the compressor and an inlet communicating with the evaporator, without incorporating air into the system, and without loss of refrigerant from the system, which comprises operating the compressor to reduce the pressure in the check valve below atmospheric pressure, venting the inlet side of the check valve to a source of liquid refrigerant below the liquid level of said source, sucking refrigerant through the check valve into the compressor, and arresting any back flow of material out of said compressor.

RALPH F. PEO.
